US0D1055614S

(12) **United States Design Patent** (10) Patent No.: **US D1,055,614 S**
(45) Date of Patent: ** Dec. 31, 2024

(54) **TOASTER**

(71) Applicant: **GUANGDONG MIDEA CONSUMER ELECTRIC MANUFACTURING CO., LTD.**, Foshan (CN)

(72) Inventors: **Xianan Liu**, Guangdong (CN); **Xi Peng**, Guangdong (CN); **Chenglong Wu**, Guangdong (CN)

(73) Assignee: **GUANGDONG MIDEA CONSUMER ELECTRIC MANUFACTURING CO., LTD.**, Foshan (CN)

(**) Term: **15 Years**

(21) Appl. No.: **35/517,014**

(22) Filed: **May 5, 2022**

(80) **Hague Agreement Data**

Int. Filing Date: **May 5, 2022**

Int. Reg. No.: **DM/220676**

Int. Reg. Date: **May 5, 2022**

Int. Reg. Pub. Date: **May 5, 2023**

(30) **Foreign Application Priority Data**

Nov. 19, 2021 (CN) 202130766285.0

Nov. 19, 2021 (CN) 202130766406.1

Dec. 9, 2021 (CN) 202130813317.8

Primary Examiner — Andrew Kerr

(57) **CLAIM**

The ornamental design for a toaster as shown and described.

DESCRIPTION

The patent or application file contains at least one drawing executed in color. Copies of this patent or patent application publication with color drawings will be provided by the Office upon request and payment of the necessary fee.

3.1 : Perspective

3.2 : Front

3.3 : Back

3.4 : Left

3.5 : Right

3.6 : Top

3.7 : Bottom

3.1 to 3.7 show a toaster according to our claimed design. The portions of the design shown in the color red are for the purpose of illustrating portions of the toaster that form no part of the claimed design.

1 Claim, 7 Drawing Sheets
(5 of 7 Drawing Sheet(s) Filed in Color)
